H. M. CRAWFORD.
ELECTRIC WATER HEATING SYRINGE.
APPLICATION FILED DEC. 7, 1911.

Patented May 14, 1912.

1,026,564.

UNITED STATES PATENT OFFICE.

HARRY M. CRAWFORD, OF LIMA, OHIO.

ELECTRIC WATER-HEATING SYRINGE.

1,026,564.

Specification of Letters Patent. Patented May 14, 1912.

Application filed December 7, 1911. Serial No. 684,389.

To all whom it may concern:

Be it known that I, HARRY M. CRAWFORD, a citizen of the United States, residing at Lima, in the county of Allen and State of Ohio, have invented certain new and useful Improvements in Electric Water-Heating Syringes; and I do declare the following to be a full, clear, and exact description of the invention, such as will enable others skilled in the art to which it appertains to make and use the same.

This invention relates to improvements in electric water heating syringes.

One object of the invention is to provide a syringe or irrigator of this character having a water controlling valve adapted to be opened by the switch or circuit closer of the electric heating apparatus of the syringe simultaneously with the closing of the electric circuit.

Another object is to provide a device of this character which will be simple, strong, durable and inexpensive in construction, efficient and reliable in operation, which may be connected directly with the city water supply and the water heated before being discharged from the instrument.

With these and other objects in view, the invention consists of certain novel features of construction, and the combination and arrangement of parts as will be more fully described and claimed.

In the accompanying drawings: Figure 1 is a side view of my improved syringe; Fig. 2 is a central longitudinal section thereof; Fig. 3 is a cross sectional view on the line —3 of Fig. 2; Fig. 4 is a similar view on the line —4—4 of Fig. 2; Fig. 5 is an enlarged central longitudinal section of the outer end 40 of the water heating chamber of the syringe; showing more clearly the construction and arrangement of the water controlling valve and the electric switch which opens the same.

45 In the embodiment of the invention, I provide a tubular handle 1 closed at its outer end and having secured to said end the discharge spout or tube 2 of the syringe, said handle and spout or tube being preferably 50 formed of hard rubber or similar non-conducting material. Engaged with the handle and having its end suitably secured therein adjacent to the closed end of the handle is a rubber hose 3 which forms the water heating chamber or compartment of the device. The hose 3 may be of any suitable length

and has secured in its outer end a nipple or hose connection 4 with which is adapted to be engaged the end of a flexible water supply pipe or hose 5 which is connected 60 at its opposite end with the faucet of the service pipe.

Arranged in the hose 3 is a resistance or water heating coil 6 which is preferably formed of German silver wire and has one end connected with a terminal or binding post 7 to which one of the current conducting wires 8 of an electric circuit is connected. The opposite end of the coil 6 is connected with a metal plug 9 in the adjacent end of the hose 3 and which forms part of the valve casing in which is arranged a water controlling valve 10 which comprises a ball or spherical body loosely mounted in a centrally disposed passage 11 in the plug 75 9 and is normally held in engagement with a valve seat 12 formed on the inner end of the discharge spout 2 by a coiled spring 13 arranged in the passage 11 of the plug as shown. Slidably mounted in the plug 9 and having a fluid tight engagement therewith is a valve operating plunger 14 the lower end of which is beveled or formed at an angle and is adapted to be forced between the valve 10 and its seat 12 whereby 80 the valve is unseated against the tension of spring 13 to permit the water to flow from the hose 3 through the passage 11 and discharge spout 2. The outer end of the stem 14 projects through a packed bearing or 85 gland 15 arranged on the plug 9 and through the adjacent side of the handle as shown.

With the outer end of the valve operating rod 14 is adapted to be engaged the outer 95 end of a switch 16 in the form of a spring metal bar, the inner end of which is secured to the outer side of the handle 1 and has arranged thereon a binding post 17 with which is connected the end or terminal of the other 100 conducting wire 18 of the electrical circuit. On the outer end of the spring switch bar 16 is arranged a thumb piece or knob 19 formed of rubber or other insulating material. By thus arranging the switch 16 and the valve 105 operating plunger 14 it will be seen that when the switch is depressed the same will be brought into electrical engagement with the valve operating plunger 14 thus completing the electric circuit through said 110 plunger, the plug 9 and the coil whereby the resistance occasioned by the latter will

heat the water passing through the hose 3. Upon a further depression of the switch 16 the valve operating plunger will be forced downwardly and the wedge shaped lower end 5 thereof engaged between the valve and its seat whereby the valve may be opened simultaneously with the closing of the electric circuit. As soon as pressure is removed from the switch 16 the spring action thereof will 10 retract the same while the pressure of the spring 13 will force the valve 10 into close engagement with its seat. This movement of the valve also retracts or pushes the plunger 14 outwardly in position to be again 15 engaged and depressed by the switch 16.

Secured to the handle 1 over the spring switch bar 16 is a hood or casing 20 of hard rubber, fiber or the like having in its outer end an opening 21 through which the knob 20 19 on the spring switch bar 16 projects.

The current conducting wires 8 and 18 of the electric circuit may be connected with any suitable source of electrical supply and when the hose 5 is connected with the faucet 25 of the water service pipe, it will be seen that an inexhaustible supply of water may be had which will be heated to a sufficient extent by the coil 6, while passing through the hose 3.

30 By arranging the water controlling valve and the electric switch as herein shown and described it will be seen that the flow of the water through the instrument is controlled simultaneously with the closing and opening 35 of the electric circuit, so that there is no danger of the water being overheated. The instantaneous closing of the electric circuit when the flow of water is stopped also provides for a saving of the electric current.

40 From the foregoing description taken in connection with the accompanying drawings, the construction and operation of the invention will be readily understood without requiring a more extended explanation.

45 Various changes in the form, proportion and the minor details of construction may be resorted to without departing from the principle or sacrificing any of the advantages of the invention as claimed.

50 Having thus described my invention, what I claim is:

1. In a syringe of the class described, a tubular casing, a hose secured therein, a plug arranged in the inner end of said hose and 55 having a discharge passage, a discharge spout arranged in one end of the tubular casing and communicating with the passage.

in said hose, a valve seat at the inner end of said spout, a valve arranged in the passage of said plug, a spring to hold said valve 60 in engagement with said seat whereby the flow of the water through the tube is cut off, an electric heating coil arranged in said hose and having an electrical connection at one end with said plug and at its opposite 65 end with one wire of an electric circuit, a valve opening plunger having a fluid tight sliding engagement with the plug in said hose and in a plane at right angles to the plane of movement of said valve, and a 70 switch connected with said casing and with the other current conducting wire of the electric circuit, said switch being adapted to be brought into electrical engagement with the valve operating plunger whereby the 75 latter is depressed and the valve opened simultaneously with the closing of the electric circuit.

2. In a syringe of the class described, a tubular casing, a hose secured therein, a plug arranged in the inner end of said hose and having a discharge spout provided with a valve seat, a valve arranged in the passage or seat plug and adapted to sit on the seat in the spout, a spring for holding said valve 80 closed, a sliding plunger mounted in said plug in a plane at right angles to said spout and having a beveled inner end for engaging said valve when forced inwardly, an electric head coil arranged in said hose and having an electrical connection at one end with 85 said plug and its opposite end with one wire of an electric circuit, a plate spring secured at one end to the outer face of said casing with its free end extending over the said 90 plunger and normally spaced therefrom, a hood inclosing said spring and plunger and having an opening therein and an operating element connected with said spring and projecting through the opening in said hood, 95 said spring being connected with the upper current conducting wire of the electric circuit and adapted to be brought into an electrical engagement with the valve operating plunger to simultaneously open the valve 100 and close the circuit.

In testimony whereof I have hereunto set my hand in presence of two subscribing witnesses.

HARRY M. CRAWFORD.
